UNITED STATES PATENT OFFICE.

DYSON FULLER, OF SOUTHEND, ENGLAND.

TROUSERS AND LIKE PRESS.

Application filed June 14, 1921. Serial No. 477,606.

To all whom it may concern:

Be it known that I, DYSON FULLER, a subject of the King of Great Britain and Ireland, whose post-office address is 7 Tylers 5 Avenue, Southend, Essex, England, have invented new and useful Improvements in and Connected with Trousers and like Presses, of which the following is a specification.

This invention relates to improvements in 10 and connected with trousers and like presses and to the type in which the trousers press is combined with a chair, the press ordinarily forming part of the back of the chair. The invention has for its object to provide an 15 improved construction of press of this kind.

In accordance with one feature of the invention press members are mounted on the back of the chair by hinges disposed in such a manner that the press members open 20 lengthwise of the back of the chair. In the preferred construction these press members each consist of two slats or strips of wood or the like hinged together longitudinally so that they fold upon one another, one being 25 detachably secured to the back of the chair, say by means of bolts.

In accordance with another feature means are provided for pressing the movable slats or strips against those attached to the chair 30 back, said means including wedges or the like adapted to be inserted between the hinged slats or strips and suitable abutments on the chair.

Other features will hereinafter appear, 35 and will be pointed out in the annexed claims.

Two embodiments of the invention are illustrated in the accompanying drawings in which, Fig. 1 is a perspective view of 40 one form of the improved combined trousers press and chair with the press members in open position. Fig. 2 is a detail in perspective of one of the press members detached, and Fig. 3 an end elevation with the 45 hinged strip or slat in half-opened position. Fig. 4 is a plan of the chair seat with the back feet removed and with the wedge members in their effective position. Fig. 5 is a 50 front elevation of the chair with the hinged strips or slats closed and the wedge blocks pressed into position flush with the chair seat. Fig. 6 is a side elevation of the chair 55 with the press in closed position. Fig. 7 is a perspective view of a chair showing associated various means, any or all of which

may be employed, for imparting pressure to the hinged slats.

As shown in Figs. 1 to 6 to the back legs *a* of the chair near the upper and lower ends are fitted strips of wood *b* or the like with slots or the like *c* in which may engage bolts *d* carried by the one portion of each press member. These press members each consist of two strips of wood or the like *e* *e'* hinged opposite one another, the one strip *e* being secured by the bolts *d* and wing nuts *d'* to the cross members *b*, the hinges *f* being fitted with the pins or pivots thereof disposed on or near the outer surface of the movable strip so that when the movable strip *e'* is folded into closed position, a lateral movement of such strip takes place imparting a slight lateral stretching movement to the trousers inserted between them.

The folding strip *e'* in lieu of being hinged directly to the strip *e* may, as shown, be hinged to a separate member *g* connected by means of spring pressed bolts *h* to the strip *e* fixed to the back whereby a suitable method of allowing yielding movement on pressure being applied to the movable strip *e'* is obtained. In the arrangement shown space is provided between the back of the chair seat *i* and the back feet *a* of the chair to permit of the movable strips *e'* being 80 opened for the insertion of the trousers to be pressed. To the sides of the seat frame are hinged blocks *k* adapted to serve as wedges and to be turned down into position flush with the chair seat to compress between the strips *e* *e'* the trousers to be pressed, the blocks in this position contributing to the 85 chair seat.

In lieu of providing a large opening in the chair seat as shown, I may provide a mere passage for the trousers and arrange that the hinged strips *e'* be interrupted or slotted to correspond with the thickness of the chair seat to permit of the strips *e'* being turned outwards for the insertion of the trousers and I may provide in lieu of the wedge shaped blocks *k* other means of compressing the trousers between the strips *e* *e'*. In Fig. 7 I have shown various devices by which this pressure may be exerted. These devices may be used either separately or together. As examples of the means which may be employed for this purpose I have shown spring clips *l* adapted to embrace the back feet *a* of the chair, and 90

- to press the strips e' tightly against trousers held between them and the strips e . I have also shown a transverse bar m between which and the strips e' may be inserted wedges n .
- 5 Hinged extensions o attached to the arms of the chair are also shown for this purpose, and beneath the chair seat I have shown wedge pieces or blocks p as being inserted between abutments attached to the back feet
- 10 and the movable strips e' .

As shown in Fig. 6 there is provided in conjunction with the press a trousers gripping device by which the trousers may be held securely while they are being pulled at the other end, and the press members are being closed whereby to ensure stretching of the trousers. This trousers gripping device may consist of buttons attached to the chair back at the top and adapted to grip the trousers. In the form shown, however, the trousers gripping device comprises plates, washers, buttons or the like q carried on bolts r and pressed by means of springs s against a ledge or top plate t projecting behind the chair back at its upper end, the trousers being adapted to be gripped between the plate or washer q and the adjacent surface of the projecting ledge or top plate t .

The top plate t and a corresponding lower plate t' project forwardly so as to lie flush with the under or fixed slat or strip and thereby ensure continuity of surface presented to the trousers. These plates also act as guides for the press members.

35 In use of the trousers press shown in the drawings the strips e e' adapted to engage the trousers and to be closed to form the crease are moved into position along the guides or slots in the chair back and fixed by means of the wing nuts d' in a position to suit the width of trousers to be pressed. The strips e' are turned outwards and the trousers hung over the front side of the back of the chair. The trousers are secured to the projecting ledge or top plate t by means of the plates or washers q . Then the trousers are pulled straight by pulling the bottom edge. Then the strips e' are turned inwards and the wedges or the like are pressed downwards into the space between the back of the seat and the chair back. The chair may now be used as an ordinary chair.

It will be obvious that the strips or slats which come opposite each other may differ in width, and that pressure may be applied

first to one side and then to the other of the trousers thus allowing for adjustment of the trousers.

The space afforded by removal of a part of the chair seat may vary. In fact the whole seat may be removable or replaceable so that when replaced it serves as the wedge to bring pressure on the movable strips or slats and thus on the garment.

What I claim and desire to secure by Letters Patent of the United States is:—

1. A combined chair and trousers press comprising a chair having an opening between the chair back and the chair seat, a pair of press members each composed of two vertical pivotally connected slats, positioned adjacent, and supplementing, the chair back and extending through said opening to below the seat level, means for adjustably securing one slat of each pair of press members to the chair back, the other slat of each pair being free to swing away from its companion slat and into the opening, wedging blocks hinged to the side edges of the seat, and swingable inwards into the opening and between the back edge of the seat and the slats, whereby to thrust the swinging slats into pressing relation with the other slats and also to supplement the normal seat area.

2. A combined chair and trousers press comprising a chair having an opening between the chair seat and the chair back, a pair of press members each composed of two vertical pivotally connected slats supplementing the chair back and extending below the seat level, means for adjustably securing one slat of each pair to the chair back the other slat of each pair being able to swing open and into the opening, wedging blocks hinged to the side edges of the seat for swinging inwards into the aforesaid opening and between the back edge of the seat, and the slats, whereby to thrust the swinging slats into pressing relation with the other slats, and also to supplement the seat area, said wedging blocks assuming a flush position with respect to the seat, whereby to receive side support from the seat edge, a top plate on the chair back, and spring controlled clips mounted on said top plate to hold the articles for stretching between the slats of each pair of press members before the pressing operation.

DYSON FULLER.
